UNITED STATES PATENT OFFICE.

JOHN VANES, OF BRAZIL, INDIANA.

DESIGN FOR A FIRE-BOX FOR BOILERS.

SPECIFICATION forming part of Design No. 31,010, dated June 13, 1899.

Application filed May 13, 1899. Serial No. 716,748. Term of patent 7 years.

To all whom it may concern:

Be it known that I, JOHN VANES, a citizen of the United States, residing at Brazil, in the county of Clay and State of Indiana, have invented a new and original Design for a Fire-Box for Boilers; and I do hereby declare the following to be a full, clear, and exact description of the invention, such as will enable others skilled in the art to which it appertains to make and use the same.

This invention relates to a new and original design for the fire-box of a steam-boiler, reference being had to the accompanying drawings, in which—

Figure 1 is an elevation. Fig. 2 is a top plan view.

As shown in the accompanying drawings, the design consists of the lower cylindrical portion A, connected to a frusto-conical portion B, to the end of which is secured a sec-

ond comparatively small cylindrical section C, as shown. At a point intermediate the ends of the portion A of the fire-box is an elliptical opening A'. The frusto-conical portion B of the box is shown with angle-irons 25 B' upon the sides thereof, and the upper end of the small cylindrical portion C is provided with a series of perforations c.

Having thus fully described my invention, what I therefore claim as new, and desire to 30 secure by Letters Patent, is—

The design for a fire-box, substantially as herein shown and described.

In testimony whereof I affix my signature in the presence of two witnesses.

JOHN VANES.

Witnesses:

CHARLES JONES,
WILLIAM PAUL ZIMMERMAN.
